UNITED STATES PATENT OFFICE.

PHILIPPO L. E. DEL FUNGO-GIERA, OF NEW YORK, N. Y.

MINE OR TORPEDO.

1,228,754.

Specification of Letters Patent.

Patented June 5, 1917.

Application filed May 11, 1916. Serial No. 96,802.

To all whom it may concern:

Be it known that I, PHILIPPO L. E. DEL FUNGO-GIERA, a citizen of Switzerland, and a resident of New York city, New York, have invented a new and useful Improvement in Mines or Torpedoes, which invention is fully set forth in the following specification.

The present invention is an improvement 10 in automobile mines or torpedoes, and the object of the present invention is to provide a device of this character which will remain submerged at a predetermined depth and will automatically travel in a regular 15 zig-zag path.

The invention will be better understood by reference to the accompanying drawings, wherein—

Figure 1 is a longitudinal vertical section; 20 Fig. 2 is a top plan view; and Fig. 3 is a rear end elevation.

Fig. 4 illustrates diagrammatically an arrangement whereby the propellers may be operated periodically and alternately.

Referring to the drawings, wherein like reference numerals indicate like parts, 5 indicates the charge-containing portion of the mine or torpedo, and 6 indicates the part of the mine in which the motor and other 25 motive mechanism is contained. These two parts are connected together in any suitable manner, as by means of bolts 7, a packing 8 being preferably interposed between said parts. A wall 10 separates the explosive 30 chamber from the motor chamber.

The mine is provided with two propellers 11 and 12, one arranged on each side of the medial fore-and-aft line. Each propeller is mounted on a shaft 13 that passes into the 35 mine through a stuffing box 14, and each shaft is connected to a suitable motor 15 in any desired manner. This motor may be either spring, electric, or driven by any desired power, and is equipped with any suitable 40 means for first driving one propeller for a predetermined period, then automatically disconnecting said propeller and then driving the other propeller for a predetermined period. The propellers are success- 45 sively, periodically and automatically operated, so that, when the mine is placed in the water and headed for any desired point, it will travel to that point in a zig-zag fashion, thus largely increasing the chances of 50 the mine or torpedo hitting the object for which it is intended or aimed. The motor

and mechanism for successively and automatically driving the propellers are only illustrated in the drawings diagrammatically, inasmuch as any suitable mechanism 55 may be used for this purpose. Referring to Fig. 4, a suitable arrangement for operating the propellers periodically and alternately is shown by a diagram wherein 50 and 51 represent the two branches of an 60 electric circuit leading from any suitable source of power. The former of these branches is divided, as shown at 52, 52', and connected with the two electric motors 15 and 15', from which extend the propeller 70 shafts 18. The latter of these branches leads to a disk 53 of electrically conductive material, said disk being provided at spaced points on its periphery with two inserts 54 and 54' of insulating material. Contact 75 strips or springs 55 and 55' are in circuit with the motors by connections 56 and 56', and are designed to alternately engage the periphery of disk 53 and the inserts 54 and 54'. To oscillate the disk 53 in opposite directions intermittently, to engage alternate contacts 55 and 55' with the periphery of the disk or the inserts 54 and 54' alternately, said disk is mounted on an oscillatory shaft 57 which carries a sleeve 58 provided with pins 59 and 59'. Said pins are alternately engaged by pins 60 and 60' on speed-reduction gearing 61 and 62 driven from the propeller shafts as shown. Assuming motor 15 to be running, contact 55 engages the periphery of disk 53, while contact 55' engages insert 54'. Current is now led to motor 15 through wire 51, disk 53, contact 55, and wire 56, and out through wires 52 and 50. After a predetermined 90 time, pin 60 is rotated by reduction gearing 61 to a position where it engages pin 59 and oscillates shaft 57 and disk 53, moving insert 54 under contact 55 and engaging contact 55' with the periphery of said disk. Current is then led to motor 15' through wire 51, disk 53, contact 55' and wire 56', and out through wires 52' and 50. After a predetermined time, pin 60' is rotated by reduction gearing 62 to a position where it 100 engages pin 59' and oscillates shaft 57 and disk 53, restoring the mechanism to the condition first assumed.

Preferably, the inner end of each shaft 13 is provided with a bevel pinion 16 which 110 meshes with a bevel gear 17 mounted on one end of a shaft 18 that passes through a sup-

porting wall 19 and which is driven by the motor 15.

The wall 19 is secured in place in any desired manner, as by angle plates 20 and 5 bolts 21.

The mechanism for firing the torpedo or mine is mounted at the front end thereof and includes a firing pin 22 provided with a contact head 23. This firing pin projects 10 through a stuffing-box 24 and a housing 25 for said stuffing-box. Preferably, a spring is also carried by said housing 25 and associated with said firing pin 22, in order to hold the same normally in the position shown 15 in Fig. 1.

The firing pin also projects through a guide 26 between which and a wall 27 is carried the priming charge. Preferably, a container 28 incloses a supply of sulfuric or 20 other suitable acid 29, and a container 30 carries an explosive 31 which will be detonated when the acid in the container 28 contacts therewith. Obviously any other suitable type of contact firing mechanism 25 may be employed, if desired. Openings 32, 33 are provided in the wall 27, in order that the main explosive charge may be detonated promptly upon the breaking of the container 28 by the firing pin 22. The wall 30 27 is secured in place in any desired manner, as by the bracket members 34 and bolts 35 and 36. Any desired explosive may be carried by the torpedo or mine, but preferably there is employed tri-nitro-toluol, wet 35 gun-cotton, or dynamite. Before the explosive is placed in the mine, the latter is preferably coated interiorly with liquid glass to protect the charge, and on top of the main explosive charge there is preferably placed 40 a quantity of mono-nitro-naphthalene. When the mine is exploded, the mono-nitro-naphthalene gives off a dense black smoke which completely envelops a vessel or other object struck, thus preventing signaling, 45 pair, or rescue.

Means are provided for maintaining the mine at a desired degree of submergence, and preferably these means consist of a weighted or ballast fin or keel 37 which is 50 movable into and out of guides 38 and 39. Suitable retaining means are provided for holding the fin in place in its guides and, as here shown, bolts 40 are provided for this purpose.

55 The greater the depth at which it is desired to drive the mine, the heavier is the fin employed; and preferably a set of two or more fins of different weight is always available.

60 A safety valve 41 normally closes an opening in the rear of the mine, and this valve, which is mounted on a stem 42, is normally held in its closed position by a spring 43.

The rear end of the valve stem 42 engages 65 a housing 44 which is secured to the wall

19 by bolts or other suitable retaining means 45. This housing is of suitable structure, such that, at the end of a predetermined period of submergence (as for example twenty-four hours), the housing will collapse or be

70 destroyed, thus permitting the safety valve 41 to open. Thus the housing 44 may be made of frangible material and provided interiorly with timing mechanism, diagrammatically shown at 46, such mechanism having a suitable device, as the hammer indicated at 47, to break said housing after a predetermined time. Thereupon the mine is 75 flooded and sinks to the bottom, thereby preventing accidental discharge.

80 While, for the purpose of illustration, one expression of the inventive idea has been shown and described in detail, it will be understood that the inventive idea is susceptible of various mechanical embodiments 85 within the limits of the appended claims.

What is claimed is:—

1. In a traveling mine or torpedo, the combination of motive mechanism, two propellers one arranged on each side of the medial fore-and-aft line of the torpedo, and means whereby said propellers are automatically operated to drive the torpedo periodically and alternately in directions inclined to a medial course.

90 2. In a traveling mine or torpedo, the combination of motor mechanism, two propellers one arranged on each side of the medial fore-and-aft line of the structure, and means for automatically driving said propellers alternately and periodically.

95 3. In a traveling mine or torpedo, the combination of motive mechanism, two propellers one arranged on each side of a medial fore-and-aft line of the torpedo, and means to automatically and periodically drive said propellers in succession to propel the torpedo alternately in directions inclined to a medial course.

100 4. In a traveling mine or torpedo, the combination of motor mechanism, means for driving said mine in a zig-zag path, and means for interchangeably securing to the body of said mine or torpedo any one of a plurality of substitutive ballast fins or keels 105 of different weight to predetermine the depth of submergence thereof.

110 5. In a mine or torpedo, a body containing a bursting charge, a fin or keel, and means for interchangeably securing to said body any one of a plurality of substitutive ballast fins or keels of different weight to predetermine the depth of submergence thereof.

115 6. In a traveling mine or torpedo, the combination of motor mechanism, means for driving said mine in a zig-zag path, and means for automatically sinking the mine after a predetermined period, said means comprising a valve to admit water to the 120

125

mine, a destructible housing controlling said valve and means for destroying said housing.

7. In a mine or torpedo, a body containing a bursting charge, and means for automatically sinking the mine after a predetermined period, said means comprising a valve to admit water to said body, a destructible housing controlling said valve and means 10 for destroying said housing.

8. In a traveling mine or torpedo, the combination of a body containing a bursting charge, motive mechanism within said body, and means coacting with said motive mechanism for automatically propelling said mine 15 alternately in directions crossing a medial course at an inclination.

In testimony whereof I have signed this specification.

PHILIPPO L. E. DEL FUNGO-GIERA.
